Patented Aug. 21, 1917.

UNITED STATES PATENT OFFICE.

HAL MULLEN, OF NEW DECATUR, ALABAMA.

END SECTION FOR RADIATORS.

1,237,941.

Specification of Letters Patent. Patented Aug. 21, 1917.

Application filed February 12, 1916. Serial No. 77,935

To all whom it may concern:

Be it known that I, HAL MULLEN, a citizen of the United States, and a resident of the city of New Decatur, in the county of Morgan, State of Alabama, have invented 5 certain new and useful Improvements in End Sections for Radiators, of which the following is a specification.

This invention relates broadly to radiators 10 and more especially to an end section for a radiator.

The principal object of the present invention is to provide an end section adapted to coöperate with the ordinary commercial type 15 of intermediate sections and whereby the end section is so partitioned as to cause the heating fluid to be distributed throughout the radiator from the top portion thereof.

A further object of the present invention 20 is the provision of an end section adapted for coöperation with commercial intermediate sections whereby the radiator may be piped for return flow at the same end as the inlet, or the radiator may be tapped for a flow 25 wherein the inlet is at one end of the radiator and the outlet is at the other end thereof.

Still more specifically the object of the present invention is to provide a construction 30 wherein the end section of the radiator is partitioned in such manner as to present independent vertical columns, one column of which is tapped for the inlet and the other column of which is tapped for the outlet.

Still other and further objects of the present 35 invention will in part be obvious and will in part be pointed out hereinafter in the specification following by reference to the accompanying drawings forming a part of the said specification, and wherein 40 throughout the several figures of the drawings like characters are used to represent like parts.

Figure 1 is a perspective view showing a radiator with intermediate sections omitted 45 to more clearly disclose the circulatory system. Fig. 2 is a sectional view taken on lines A—A of Fig. 1. Fig. 3 is a sectional view taken on lines B—B Fig. 2. Fig. 4 is a perspective view illustrating the circulatory system where the inlet is at one end and the outlet is at the other end of the radiator. 50 Fig. 5 is a sectional view taken on lines C—C Fig. 4.

It is usual in the art of hot water and 55 steam heating to provide radiators wherein each section of the radiator, including the

end sections, is a hollow member having a continuous or unbroken passage except for intermediate walls provided to increase the radiating surface. In such constructions 60 where the sections are connected to provide a continuous opening through the upper portion, there is no positive flow of the fluid through the upper connections. The sections in this form of radiator are filled with a 65 heating fluid and circulation in the radiator, if any, is due to thermal conditions. Furthermore, in radiators of the character specified it is necessary to provide an inflow at one end and an outflow at the other end. 70

The device comprising the construction of the present invention, which will be more clearly described hereinafter, comprises an end section adaptable to conform to the common commercial intermediate sections and 75 whereby the end section is partitioned so that it comprises two independent vertical columns or legs, both of which lead to a connector opening at the top and one of which columns is provided with an inlet opening 80 at the bottom, the other of the said columns being provided with outlet openings. By this construction it will be noted that the fluid is at least compelled to travel to the top of the end section, and since the first outlet opening is provided at this point the fluid is given the first opportunity to distribute 85 itself from the top of the radiator.

Referring now to the drawings and more particularly to Figs. 1, 2 and 3, the end section X comprises body walls 1 which terminate at the lower end with integral feet or legs 2. In the form illustrated in Figs. 1, 2 and 3 draft openings 4 are provided, as is common in the art, to facilitate radiation. 90 Intermediate the body walls front and back is provided a lower partition 5 and intermediate one pair of draft openings is provided an upper partition 6. It will be noted that the partitions 5 and 6 divide the end section X into vertical columns Y and Z. The upper end of the vertical columns, and in the common zone thereof, is provided on the back of the end section X a connector opening 7 which is adapted to coöperate 95 with the connector opening in the ordinary radiator section W. The bottom of the vertical column Y is preferably provided with one inlet opening 8 which is located on the front side of the end section X. The vertical column Z is provided at its lower end with three openings 9, 10, and 11, any one 100

or all of which may perform the function of outlet openings. The opening 10 it is to be noted is at the back of the end section X and the openings 9 and 11 are at the front thereof.

Referring to the Figs. 1, 2 and 3 it will be noted that the inlet opening 8 is indicated as being provided with a supply pipe 12 that may be provided with a suitable valve 14. It is also to be noted that the opening 11 is provided with an outlet or return pipe 15. In these figures of the drawings referred to the circulation of the heating fluid is indicated by the arrows G. It will be noted that the fluid upon entering the column Y through the supply pipe 12 makes a vertical direction to the connector opening 7 from which opening the intermediate sections W are filled. The circulation of the fluid will be through the intermediate sections beginning at the upper portion thereof and returning through the lower portion and out through the return pipe 15. The fluid will travel up the vertical column Y and a portion thereof will travel down the vertical column Z but this local circulation is not sufficient to greatly impair the economy and efficiency of this construction. It will be noted that the Figs. 1, 2 and 3 illustrate a construction wherein the end section is utilized for piping wherein both the inlet and outlet are tapped into one end section of the radiator and where this is desirable the outlet opening 9 is preferably stopped by a screw plug 16. This opening 9 is aligned with connector opening 10, and thereby permits a connector wrench to be inserted to enable a workman to connect the several sections together. The opening 9 in the end section is necessary in order to provide an opening aligned with the lower line of the radiator to enable the various sections to be connected together. Since it is common in the art to surround radiator pipes with rings or washers where these pipes pass through flooring it is desirable that the pipes be separated sufficiently to enable these rings to be positioned without overlapping and furthermore it is desirable to lead the circulating medium toward the outer edge or side of the radiator section. For this reason the opening 11 is provided which opening enables the inlet and outlet pipes to be properly connected to the single end section to secure the most practical and efficient result.

Referring now to Figs. 4 and 5 it will be noted that the opening 8 is provided with an inlet pipe 17 and suitable valve 18, and that the openings 9 and 11 are stopped by means of screw plugs 16. In this type of construction the opposite radiator end section, which may be of the ordinary type, is provided with the outlet or return pipe 19. The travel of the heating fluid is substantially

that indicated by the arrows H, when the parts are connected with the inlet at one end and the outlet at the other end of the radiator.

From the foregoing it will be noted that my invention relates to a radiator construction facilitating the piping as convenience or circumstances may demand and also provides for a more thorough and better distribution of the heating fluid throughout the entire radiator.

Realizing that it is possible to vary the physical embodiments of my invention without departing from the spirit thereof I desire that the specific constructions herein disclosed shall be considered as illustrative and not in the limiting sense.

Having thus described my invention what I claim is:

1. As an article of manufacture, a radiator end section comprising a member provided with body walls to constitute a hollow heating fluid container, a partition extending transversely and upwardly from the bottom of the said hollow member thereby dividing the same into a plurality of vertical columns, one on each side of the radiator, one of said columns being provided adjacent the lower end thereof with an inlet opening on the front face of the section, the other of said columns being provided with openings one of which is located on the rear face and the other of which is located on the front face and may comprise an outlet opening, and the top of said end section being provided with a connector opening in the rear wall thereof, said connector opening being above said partition and in a zone common to both of said vertical columns.

2. As an article of manufacture, an end section for a radiator, comprising a hollow fluid containing member, a partition extending from the bottom to adjacent the top of said member to provide a pair of vertical columns one on each side of the radiator, said radiator section being provided at its lower end and on the front face thereof with three aligned openings two of which enter into one of said columns, said radiator section being also provided on its rear face with connector openings, one at the upper end of said section and the other at the lower end of said section to enable said section to be connected with inlet and outlet pipes on one side and with ordinary commercial intermediate sections on the other side, substantially as described.

3. As an article of manufacture, an end section for a radiator comprising a member provided with integral body walls to constitute a hollow container for a heating fluid, a partition extending from the bottom thereof upwardly and terminating short of the upper wall to divide said container into a pair of vertical columns having a common

zone adjacent the upper end of the radiator, the lower end of one of said columns being provided with a pair of outlet openings on the front wall of the radiator end section, 5 said column being provided with a connector opening in the rear wall of the radiator, the other of said columns being provided with an inlet opening in the front wall of said radiator, and the upper end of said 10 radiator being provided with a connector opening in the rear wall thereof, said end section being constructed to permit inlet and outlet connections to be made with the front wall of the end section and to co- 15 operate with the ordinary commercial intermediate sections.

4. As an article of manufacture, a hollow radiator end section having aligned inlet and

outlet connector openings in the front and rear walls respectively adjacent the bottom 20 portions thereof, a partition located at one side of said openings and extending transversely and upwardly within said end section and terminating short of the top thereof to divide the same into two vertical compartments entirely independent at their lower ends and interconnected at their upper ends by a common zone, said section having an outlet from said common zone adapted to be connected to commercial radiator sections, and each of said compartments having an opening in the front wall adjacent the bottom thereof on opposite sides of said outlet connector opening. 25 30

HAL MULLEN.
